Inventor:

O. R. Nitson

United States Patent Office.

O. R. NITSCH, OF NEW YORK, N. Y.

Letters Patent No. 94,633, dated September 7, 1869.

IMPROVEMENT IN FANS.

The Schedule referred to in these Letters Patent and making part of the same.

To all whom it may concern:

Be it known that I, O. R. NITSCH, of New York city, State and county of New York, have invented a new and improved Fan; and do hereby declare that the following is a full and exact description thereof, reference being had to the accompanying drawings, and the letters of reference marked thereon.

Figure 1 represents the fan when opened.

Figure 2 is a sectional view of the fan when closed.

The nature of my invention consists in attaching a pulley to a shaft or pivot, fastened to the upper lid of the fan, which is connected, by one or more bands or ribbons, to the inner and lower lids, and thus readily opens the fan by pulling the cord, which is wound once around the pulley.

A is the lower lid, to which the case or box B is fixed.

The pivot or shaft C is secured to the upper lid D by splint or in any suitable manner, so that when the pulley E, fastened to the other end of pivot or shaft C, is turned by the cord F, of which the one end is

fastened to the pulley E, and wound once around the same, the upper lid D describes a circle, or a portion of it, as much as desired, and by the means of one or more bands or ribbons, G, which are attached to the inner and outer lids, opens the fan, arranging the inner lids H successively, until the cord F is entirely unwound.

When closing the fan, the cord is wound up again, thus giving an easy and comfortable method of opening the fan.

What I claim as my invention, and desire to secure by Letters Patent, is—

As a new article of manufacture, a fan, whose leaves are attached to one another, and pivoted at their inner ends, the outer leaves being rigidly attached to the said pivot, and operated to spread the fan by means of a pulley and cord, substantially as described.

O. R. NITSCH.
